CARD INDEX

Benjamin G. Rand, Glendale, Calif., assignor to
Remington Rand Inc., Buffalo, N. Y.

Application October 12, 1937, Serial No. 168,630

4 Claims. (Cl. 129—16.5)

This invention relates to improvements in card indexes and particularly to constructions where the cards stand on edge in a drawer and are provided for offsetting relative to one another to bring a marginal portion of each card into visible indexed relation.

The present invention comprehends the provision of clips secured to one margin of each card of a series arranged in pairs in spaced relation, each provided with slots and projections so that one card may have the projections of the clips thereon interengaged with the slots in the clips of the next card by flexing the card to engage the projections in the slots.

The invention provides a clip structure for attachment to the margin of a card formed from a folded strip of material, so that two clips may be mounted in spaced relation on one margin of a card, each clip having a projection formed thereon and each formed to provide a slot, so that the two projections on the spaced clips of one card may be used to cooperate by slidably engaging in the slots of the clips on another card to interconnect the cards for limited relative edgewise movement to offset one card with respect to the other to expose their margins in visible indexed relation.

The invention includes the provision of a special clip structure in which each clip is formed from a folded strip having the ends of the strip secured to the margin of the card while the folded portion projects away from the edge of the card. One side of the folded strip is formed with a removed portion extending from the fold to the edge of the card to provide a slot between the folded portions of the strip, to receive a tongue on a similarly constructed strip formed from the fold portion of the strip opposite to that having the removed section. A pair of these clip structures are formed in opposite relation to provide oppositely extending tongues and slots so spaced that the tongues on one card will slidably engage in the slots of the next card, in such a way, that the tongues being of less width than the length of the slots, the cards may be offset laterally with respect to one another in an edgewise direction so the opposite margin of each card will be offset in visible indexed relation.

The invention includes features residing in the details of construction of the cards and clips to secure the efficient support and operation of the cards in a series interconnected one to the other by means of the clip structures, these detailed features being more particularly pointed out in the following description and claims.

In the drawing:

Fig. 1 is a front elevation of a series of cards interconnected and offset relative to one another.

Fig. 2 is a vertical section taken on line 2—2 of Fig. 1.

Fig. 3 is a view similar to Fig. 2 showing the cards arranged in their normal position without offsetting so that the upper edges are in the same horizontal plane.

Fig. 4 is a bottom plan view of two cards showing how one card is flexed to insert the tongues of the clips into the slots of an adjacent card.

Fig. 5 shows a group of cards in perspective, with several connected cards offset in visible indexed relation, while another card is shown in detached relation but in position to illustrate the manner of attachment and relation of the parts.

A plurality of index or record cards are each designated with the numeral 1 in the drawing. 20 These cards are normally designed to stand on edge in a drawer one behind the other and be indexed by guides in a well known manner. With the present invention cards 1 are interconnected to one another to form groups of interconnected cards, the last card in the group being provided with an index tab 2 that also forms a handle by which the card may be manually raised up so as to offset all of the cards in the visible index relation illustrated in Fig. 1. 30

To accomplish this offsetting, each card is provided on the lower margin with clips 3 and 4 respectively. The clip 3 is formed oppositely to clip 4, otherwise the construction of each clip is identical. Each clip is formed of a strip of 35 sheet metal or other suitable sheet material folded at 5 to provide ends 6 and 7. The ends of this folded strip are engaged on opposite faces of the margin of the card and a tubular rivet 8 or other suitable means is used to rigidly secure the strip to the card with the fold portion projecting beyond the edge of the card margin as illustrated. A portion of the strip section 6 of each clip at one edge thereof is removed from a point adjacent the edge of the card to the fold portion 40 as indicated at 9. The fold portions provide a slot therebetween since they are arranged in the normal position in spaced parallel relation.

Strip sections 7 have portions offset adjacent the edge of the card to provide attaching tongues 50 10. Tongues 10 are arranged so that the upper edge of each tongue is aligned with the upper edge of the cut-out portion 9 of each clip and the width of the tongue in each case is less than the length of the slot in the clip. The tongues on the 55

clips carried by each card extend outwardly in opposite directions in parallel relation to the card and the tongues are offset from the strip sections 7 away from the plane of the card a sufficient distance to receive strip sections 6 of other clips between the tongues and the strips from which they are formed. Each tongue is formed so that its base or junction with strip 7 is slightly inwardly of the vertical edge of cut-out 9 in strip 10 section 6.

By flexing one card intermediate clips 3 and 4 as shown in Fig. 4 the distance between tongues 10 on the pair of clips carried by the card can be shortened so that it is less than the distance between 15 the outer edges of the cut-out sections in the corresponding clips of an adjacent card and by this method the tongues can be engaged in the slots formed in the clips of an adjacent card below the edge of the card. The tongues are formed 20 at the rear face of the card and as a result the rear card may be moved upwardly with respect to the next card in front to the extent permitted by the length of the slots in the clips so that when the fold portions at the bottom of a pair of clips 25 on one card engage the lower edges of the tongues on the next adjacent card this upward movement of one card in edgewise relation to its adjacent card is arrested. Where a series of these cards are interconnected and the rearmost card is 30 moved upwardly in edgewise relation as shown in Fig. 1 the cards will be successively offset until they all have corresponding margins offset in visible indexed relation as shown by Fig. 1.

Excessive build-up by added thicknesses, in 35 addition to that of the card, is largely avoided in the construction of the character shown in the present application due to the fact that the projections are housed below the lower edges of index cards 1 in the space between fold sections 40 6 and 7 of the clips. This, of course, necessitates that the clips project below the lower margin of the card in order to provide the slots. At the same time the cut-out section in one end portion 45 of the clip enables the other side to form a backing to receive the tongue of the adjacent clip when it is interengaged in the slot so as to form an effective means of guiding the tongue into the slot in attaching one card to another.

The invention claimed is:

- 50 1. A card index, comprising a plurality of cards normally adapted to be filed upright on edge, a pair of clip members secured at one end to a margin of each of said cards in spaced relation and having the opposite ends extending beyond said 55 margin and formed to provide slots beyond said margin extending perpendicular thereto, projections on said clips beyond said margin for engagement in the slots of the clips on an adjacent card for connecting said cards, said slots being longer than the transverse dimension of said pro-

jections and providing for limited relative edge-wise movement of connected cards for offsetting the opposite margins in visible index relation.

2. A card index, comprising a plurality of cards 5 normally adapted to be filed upright on edge, a pair of strip members for each card folded about one margin thereof in spaced relation and secured thereto for support solely by said card without other connection, said strip members of each pair each being formed to provide a slot extending 10 transversely to said card margin and a projection extending in an opposite direction to a corresponding projection on the other strip member, said projections being of less width than the length of said slots and said cards being flexible 15 to provide for shortening the distance between the projections on one card for engaging them in the slots of an adjacent card to interconnect said cards for limited relative edgewise movement to offset corresponding marginal portions in visible 20 index relation.

3. A card index, comprising a plurality of cards, a pair of sheet material clips for each card each formed of a strip folded to provide opposite spaced sections, the ends of said sections engaging 25 opposite faces of a card margin, said pair of clips being mounted in parallel spaced relation on said card margin, one section of each clip being formed beyond the card margin of less width than the opposite section and providing a slot extending 30 laterally to said card margin between said sections, the slot in one clip extending opposite to the slot in the other clip, and a projection formed on each clip in said opposite section, said projections being of less width than the length of said 35 slots, the projections on said clips extending in opposite directions and said cards being flexible for shortening the distance between the ends of said projections on one card to engage them in the slots of the clips on an adjacent card to inter- 40 connect said cards for relative edgewise displacement to offset corresponding margins thereof in visible index relation.

4. A card index, comprising a plurality of cards, a pair of sheet material clips for each 45 card mounted in spaced relation on one margin thereof and having one end of each clip projecting substantially beyond the edge of said card, each clip having a slot on one side and a tongue offset laterally on the other side beyond said card 50 margin, said tongues being of less width than the length of said slots, the slots and tongues on each clip of a card extending in opposite directions, and the cards being formed of flexible material for the flexing of one card to engage the projections in the slots of an adjacent card for connecting said cards for limited relative edgewise movement to arrange corresponding marginal portions in visible index relation.
